(57) **CLAIM**

The ornamental design of a brick, as shown and described.

DESCRIPTION

FIG. 1 is a perspective view of a brick in accordance with my design, and showing the front face of the brick;

FIG. 2 is a rear elevational view of my design;

FIG. 3 is a front elevational view thereof;

FIG. 4 is a top plan view thereof;

FIG. 5 is a bottom plan view thereof;

FIG. 6 is a side elevational view as viewed from the right side of FIG. 1;

FIG. 7 is a side elevational view as viewed from the left side of FIG. 1;

FIG. 8 is a perspective view of the brick shown in FIG. 1, but showing the rear face of the brick;

FIG. 9 is a perspective view showing the rear face of a brick similar to the brick shown in FIGS. 1-8, but having a smooth front face;

FIG. 10 is a rear elevational view of the brick shown in FIG. 9;

FIG. 11 is a front elevational view thereof;

FIG. 12 is a bottom plan view thereof;

FIG. 13 is a top plan view thereof;

FIG. 14 is a side elevational view as viewed from the left side of FIG. 9;

FIG. 15 is a side elevational view as viewed from the right side of FIG. 9; and,

FIG. 16 is a perspective view similar to FIG. 9, but showing the front face of the brick.
